UNITED STATES PATENT OFFICE

VERNON FOWLER HOOPER, OF OSSINING, NEW YORK, ASSIGNOR TO LORD & BURNHAM
CO., OF IRVINGTON, NEW YORK, A CORPORATION OF NEW YORK

SASH ACTUATING DEVICE

Application filed February 28, 1931. Serial No. 519,314.

This invention relates to sash actuating mechanism for greenhouses and industrial buildings, but it may be employed in other structures.

One of the objects of this invention is to provide mechanism for opening and closing a sash, which mechanism is simple and effective in operation.

A further object is to provide a sash actuating device which occupies a relatively small amount of space, having the parts preferably so disposed that the actuating mechanism may be mounted directly upon the roof rafters, side columns or posts or other supporting members, in relatively close relation to the sash to be operated and in such manner that the actuating mechanism is contained entirely between an operating shaft and the sash to be opened so that no parts of the operating mechanism project beyond the line shaft and into the building structure in which the sash actuating device is employed. When the actuating mechanism is mounted directly upon the roof or side rafters, the necessity for use of supporting brackets is eliminated. This is of advantage in greenhouses as it minimizes objectionable shadow effects.

A further object is to provide a sash actuating device in which a maximum sash opening may be readily obtained by a minimum movement of the operating shaft. In accordance with the present invention the maximum sash opening may be obtained by a one-fourth rotation of the line shaft or through an arc of 90°.

A further object is to provide a sash actuating device which, in addition to having the advantages above set forth, will exert a powerful pressure in holding the sash in tightly closed position to prevent rattling and chattering of the sash, particularly when the wind is blowing.

In a general way, the above objects are accomplished by providing in combination with a line shaft and a pivoted sash, a plurality of arms, one of which is freely rotatable upon the line shaft, the other arm being adjustably fixed upon the line shaft, the arms being disposed on opposite sides

of the line shaft when the sash frame is in closed position, and in then providing a link connecting the freely rotatable arm and the sash, and a second link connecting the other adjustably fixed arm, and the link.

One selected embodiment of the invention is shown in the accompanying drawing for purposes of illustration, it being understood that various changes in detail construction, arrangement and adjustment of parts may be made, without departing from the spirit and scope of the invention.

In the drawing:

Fig. 1 is a fragment of a roof section of a structure, in side elevation, partly in section, showing the general arrangement of the sash actuating mechanism in closed position, and also in open position, the open position being indicated by the dot and dash line.

Fig. 2 is a fragment of vertical section of a structure showing the sash actuating mechanism applied to a side sash frame, and showing the line shaft carried directly by the side rafter.

Fig. 3 is a perspective showing the line shaft and the actuating mechanism.

Fig. 4 is a vertical section taken through the line shaft, and looking generally in the direction of the arrows 4—4 in Fig. 1.

In a building having a run of pivoted sash frames, there is usually provided a power or line shaft, which extends throughout the length of the run of sash in such position that the sash actuating mechanism is interposed between the line shaft 1 and the sash 13. As shown in the drawing, the line shaft 1 is preferably rotatably carried directly in the roof rafters 15, side posts 15' or other structural member.

In certain forms of sash actuating devices heretofore employed, it has been necessary to provide independent columns, or relatively long brackets in order to support the line shaft, and afford sufficient space for the sash actuating mechanism which frequently extended into the structure, beyond the line shaft. It is one of the distinct advantages of the present sash actuating mechanism, that the entire sash operating mechanism is folded and contained between the roof or side

sash and the power line shaft which is preferably carried directly by the roof or side rafters. If desired a relatively short bracket may be employed for supporting the line shaft in relative close relative to the roof rafters or side post on which the brackets may be mounted.

In the preferred form illustrated, there is shown a plurality of arms 2-4, which are mounted upon the line shaft 1 carried directly by the roof or side rafters 15. The arm 4, is so mounted as to be rotatable relative to, and upon the line shaft 1, which is shown rotatably mounted in the roof and side rafters 15.

As shown, the end of the arm 4 comprises a plurality of spaced collar or ring-like portions 5-6 which receive the line shaft 1.

The arm 2 is adjustably fixed upon the line shaft 1 so that the arm 2, is moved upon rotation of the shaft 1. The arm is held in adjustably fixed relation upon the shaft by an adjusting set screw 3. The arm 2 is shown fixed on the line shaft 1 between the ring portions 5-6 of the arm 4. This arrangement makes a neat and compact structure. It is understood that other well-known means may be employed for rotatably mounting the arm 4 upon the shaft 1, and for mounting the arm 2 in adjustably fixed relation upon the shaft 1.

The movement of the arm 2 which is actuated by the power line shaft 1 is transmitted to the sash 13, through a plurality of links 7-8. The link 8 is pivotally connected at one end through a bracket fixture 11 to the sash frame, and is pivotally connected in a suitable manner at the point 10 to the arm 4. The link 7 is pivotally connected at one end 16 to the arm 2, and is pivotally connected at its other end 9 to the link 8, intermediate to the ends thereof. As shown, the link 7 is substantially the same length as, and is parallel to, the arm 4, and the portion of the link 8 between the points of pivotal connection 9-10 is substantially the length of the arm 2, and is disposed substantially parallel thereto. It is understood, of course, that depending upon the particular requirements, that the links and arms may be of various lengths and adjusted in various relations to obtain various effective forces and different ranges of movement.

As shown in the full line position of the parts in Fig. 1, with the sash 13 in closed position, the arm 4 rotatable upon the shaft 1, and the arm 2 adjustably fixed upon and movable with the shaft 1, are disposed on opposite sides of the shaft 1, and extend substantially in opposite directions. A powerful force is exerted by the arm 2, through the leverage of the link 7 and arm 4 upon link 8 for tightly holding the sash 13 in closed position.

The frame 13 is shown hinged at its upper

side to the cap 14 adjacent to the ridge pole.

It is understood, of course, that the sash actuating mechanism herein disclosed may be utilized for actuating a sash supported in either a vertical or horizontal position, as well as in an angular position, as illustrated in the drawing.

One of the advantages of the folding arm type or sash actuating mechanism herein disclosed is that a minimum number of pivot points are employed so that friction at these points, due to corrosion or lack of lubrication, is reduced to a minimum.

One of the advantages in providing a sash actuating mechanism which at all times occupies a space between the line shaft and the sash when in open and closed position, is that in greenhouses, the shadow effect upon the vegetation is reduced to a minimum, and in industrial structures such as ware houses or power houses, the space in the structure is conserved for either the storage of material, or the free movement of cranes, hoists and the like.

While one preferred form of the invention has been shown and described, it is understood that various changes may be made without departing from the spirit and scope of the invention as defined in the appended claims.

What I therefore claim and desire to secure by Letters Patent is:

1. In sash actuating mechanism including rafters, a line shaft rotatably supported therein and a sash, a combination of a plurality of arms mounted on said shaft, one of said arms being mounted to rotate relative to said shaft, said second arm being mounted to rotate with said shaft, a link connecting said first arm with the sash, and a second link connecting said second arm and said first named link.

2. In a device of the character described, including a line shaft and a sash frame pivotally mounted, a combination of an arm mounted to rotate on said line shaft, a second arm adjustably fixed on said shaft to rotate therewith, said arms being disposed on opposite sides of the line shaft when the sash is in closed position, a link connecting said first arm and said sash, and a second link interposed between said last named link and the arm fixed on the line shaft.

3. In sash actuating mechanism including a line shaft and a sash, the combination of a plurality of arms mounted on said shaft, one of said arms being mounted on the shaft to permit relative rotary movement between said arm and said shaft, a second arm adjustably fixed upon the shaft so as to move therewith, said second arm being disposed on the shaft side opposite to the side on which the first named arm is disposed, a link having one end pivotally connected to the sash, the other end of said link pivotally connected

to the end of said first named arm, said link disposed substantially parallel to said arm adjustably fixed on the line shaft, and a second link having one end pivotally connected to said first named link at a point intermediate to the ends of said first named link, the other end of said second link being pivotally connected to the end of said second named arm adjustably fixed to the shaft, said 10 second link being disposed substantially parallel to said first named arm.

4. In sash actuating mechanism including a line shaft, the combination of a plurality of arms mounted on said shaft, one of said 15 arms being rotatably mounted on said line shaft, the second arm being adjustably fixed on the line shaft so as to rotate therewith, said arms being disposed on opposite sides of the line shaft and extending in opposite directions when the sash is closed, and a link mechanism interposed between the ends of each of said arms, and the sash, arranged to actuate said sash upon movement of the adjustably fixed arm.

25 5. In sash actuating mechanism including an operating shaft, and a sash pivotally mounted, the combination of an arm rotatably mounted on said power shaft, said arm having a forked section at the point of connection with said shaft, a second arm mounted on the power shaft so as to rotate therewith, said second arm being mounted on the power shaft between the forked end of said 30 first arm, a link connecting the sash and the first named rotatable arm, and a second link connecting said first link and said second named arm which is fixed upon the shaft.

35 6. In sash actuating mechanism including an operating shaft, and a sash pivotally mounted, the combination of an arm rotatably mounted on said power shaft, said arm having a forked section at the point of connection with said shaft, a second arm mounted on the power shaft so as to rotate therewith, said second arm being mounted on a power shaft between the forked end of said 45 first arm, a link connecting the sash and the first named rotatable arm, and a second link connecting said first link and said second named arm which is fixed upon the shaft, said 50 second link being connected to said first link at a point intermediate to the ends of said first link and at a point spaced from the end of the first link connected to the first arm a distance equal substantially to the length of 55 the second named arm fixed on the shaft, said second link being of a length substantially the same as said first named arm.

In testimony whereof I affix my signature.

60 VERNON FOWLER HOOPER.
